UNITED STATES PATENT OFFICE.

RUSSELL C. JONES, OF BRONXVILLE, NEW YORK, ASSIGNOR TO THE GRISCOM-RUSSELL COMPANY, OF NEW YORK, N. Y., A CORPORATION OF DELAWARE.

HEAT EXCHANGER WITH SELF-DRAINING TUBE SURFACE.

Application filed April 8, 1926. Serial No. 100,520.

The present invention relates to heat exchangers and has to do particularly with the construction of the heating element of the heat exchanger in such fashion as to 5 afford a heat transferring surface of maximum effectiveness, and contemplates particularly a heat exchanger embodying a tubular heat transferring element wherein the under surface of each tube is protected from 10 condensate draining from other tubes or from other portions of the tube so that an increased capacity of the heat transferring surface is secured.

The invention pertains chiefly to that class 15 of apparatus,—such as heaters, condensers, and the like—wherein one of the heat transferring fluids is a condensable vapor such as steam, which is completely condensed on the heat transferring surfaces of the apparatus. 20 In this type of apparatus, the heat transferring element commonly consists of a plurality of closely grouped tubes which extend longitudinally of the apparatus and serve to convey through it one of the heat transferring mediums. The steam is usually admitted to the space surrounding the tubes and condenses upon the outer tube surfaces to thus effect the requisite heat transfer 25 through the tube walls to the fluid within the tubes. Tubes of circular cross-section have heretofore been used generally for heat exchangers of all kinds but tubes of different cross-section have been proposed in some instances, to secure greater surface in proportion to the cross-section of the tube and 30 for other purposes.

In my prior Patent, No. 1,549,489, granted 35 August 11, 1925, there is disclosed an oil cooler in which the tubes are formed with a longitudinal depression in at least one side so that the viscous liquid is maintained 40 in the form of a stream, all particles of which are close to the wall of the tube, with the result that an increased velocity of flow 45 is obtained to thereby prevent the formation of a film of the liquid adhering to the wall of the tube, where it would serve to prevent an effective heat transfer. In that apparatus the fluid in the shell is a cooling 50 liquid having a generally longitudinal flow through the shell so that the position of the tubes in the shell is not important. When, however, the structure shown in that patent 55 is used as a condenser or heater with steam in the space surrounding the tube, the struc-

ture is open to the objection that condensate accumulating in the longitudinal depression extending along the tubes blankets a substantial proportion of the heat transferring surface with a relatively poor conducting layer of condensate and thus materially hampers the heat transferring efficiency of the apparatus.

It is a principal object of this invention 65 to provide a heater or condenser employing heat transferring tubes in which the heat transferring surface is not impaired by a layer of condensate in the manner described. To this end the tubes are preferably provided with longitudinally extending grooves, 70 and are mounted in the heat exchanger in such fashion that the grooves face downwardly. With this arrangement, the upper surface of the tube is continuously convex and thus serves to effectively shed the water or condensation accumulating on it. The lower surface of the tube is concave and, being reentrant with respect to the upper surface, is effectually protected from the condensate draining off the upper surface of the tube or dripping from other tubes. Thus, the lower or reentrant portion of the tube surface, which amounts to approximately fifty per cent of the total heat transferring surface of the tube is effectively protected from condensate and is thus maintained at its best heat transferring efficiency. 75

By means of this invention, it is possible to provide a heat exchanger of this type which not only incorporates the advantage 90 of maintaining a large proportion of the heat transferring surface free from an objectionable film of condensate but which also possesses the advantages arising out of filming the liquid within the tubes at high 95 velocity into intimate heat transferring contact with the tube walls. This feature is of value in transferring heat between any fluids and is of particular value where the fluid within the tubes is oil or a similar liquid 100 whose viscosity changes with temperature.

It is a still further object to provide a heat exchanger which incorporates the advantages above noted and in addition provides for the inclusion in the heat exchanger 105 of an increased area of heat transferring surface corresponding to a given available circulating space for the heating steam. Due to the fact that each of the tubes is provided with a reentrant groove, the dis- 110

placement of each of the tubes is materially reduced, thus affording a correspondingly increased steam space. The tubes may therefore be installed more closely together 5 in order to take advantage of this available increase in steam space and still permit of a proper balance between the steam space available and the amount of heat transferring surface. This feature is of notable 10 value in heat exchangers employing a bowed tube construction. In apparatus of this type, an increased clearance is necessary to permit flexure of the bowed tubes under the influence of temperature change. With 15 the structure of the present application, ample clearance is obtainable without necessity of resorting to objectionably wide spacing of the heat exchanging tubes, and there is no tendency to formation of condensate 20 on the tubes.

A preferred embodiment of the invention is illustrated in the accompanying drawings in which:

Fig. 1 is a longitudinal sectional view of 25 a straight-tube apparatus embodying the present invention;

Fig. 2 is a transverse sectional view taken 30 along line 2—2 of Fig. 1, sighting in the direction of the arrows, and illustrating the construction and arrangement of the heat transferring units;

Fig. 3 is a detail view showing several 35 different forms of the tube of the present invention which may be employed, and

Fig. 4 is a modification of the invention embodied in a bowed-tube apparatus.

Referring to the drawings, 1 indicates the containing shell of the apparatus and 2 indicates the heat transferring tubes. Liquid 40 is admitted to the apparatus through the inlet opening 3 and traverses the heat transferring tubes 2, which as shown in Fig. 1 may be divided to form two successive passes. The liquid then issues from the 45 apparatus through the discharge opening 4. Heating steam is admitted through the inlet opening 5 to the space surrounding the heat transferring tubes 2 and by circulation about within the shell 1 is brought into 50 repeated contact with the tube surfaces and is condensed, the condensate being discharged from the apparatus through the opening 6 provided at the bottom of the shell 1 for that purpose. The tubes are supported at their respective ends by means 55 of suitable tube sheets 7 and 7^a, into which the ends of the respective tubes are expanded or otherwise secured. As shown, the tube sheet 7^a forms part of a floating head connecting the two passes of the heater as is common in apparatus of this class.

The construction of the heat transferring tubes 2 and the positioning of these tubes in the shell is shown in detail in Figure 2. The intermediate portion of each

of the tubes is provided with a longitudinal depression 8 which extends throughout substantially the entire portion of the tubes lying intermediate the tube sheets 7 and 7^a. The upper portion of the tube surface indicated at 9 is substantially semi-circular in section and thus presents a sloping surface from which accumulated condensate readily drains. The longitudinal depression 8 occurs at the under side of the tube and, as 75 is evident from the drawings, is protected from condensate draining off the upper surface portion 9 of the tube or dripping from other tubes. This lower groove or reentrant portion of the surface constitutes substantially fifty per cent of the total heat transferring surface of the tube and is at all times protected from an objectionable film 80 of condensate with the result that a material increase in the heat transferring efficiency of the apparatus is effected. It is evident that certain variations in the shape of the tube section may be made and some such variations are shown in detail in Figure 85 3.

The cross sectional area of the tubes is substantially reduced by reason of the provision of the groove 8. The result is that the liquid traversing the tubes is filmed out in a flat stream, all points of which are 95 closely adjacent the tube walls. This affords a particularly effective heat transfer in the case of oils and similar liquids wherein there is a tendency toward the formation of a congealed layer of liquid immediately 100 adjacent the cooling surfaces.

Due to the reduced cross sectional area of the present tubes, an increased amount of steam space is made available. This increased space is proportional to the difference between the area of the original circular cross section of the tube and the cross sectional area of that portion of the tube having the longitudinal depression 8 formed in it. This feature may most effectively be 105 taken advantage of by spacing the tubes in more closely adjacent relation.

In the bowed tube construction shown in Fig. 4 of the drawings it will be noted that the provision of the groove on the under side of each tube allows the next lower tube a greater relative freedom of movement without danger of interference between tubes. Also, this reduction in the interior volume of the shell of the exchanger of the present invention which is occupied by the tubes of the present invention constitutes a great improvement over the ordinary exchanger with plain circular tubes. For, in this latter type of exchangers, it is usually necessary to provide a large number of passes for the fluid,—sometimes as high as six,—in order to accomplish results at all approaching those effectuated by the present invention. This necessitates numerous par-

titions in the fluid-headers—that is, the oil or water headers—and naturally opposite these header-partitions, whole rows of tubes must be omitted, which radically reduces 5 the amount of surface which can be installed in the heat-exchanger. With the present design, on the other hand, it is never necessary to provide more than two passes, and frequently it is sufficient to have one pass 10 with an outside-packed, floating head.

I claim:

1. In a heat exchanger of the class described, a shell, heat transferring tubes within said shell and presenting a convex upper 15 surface and a concave lower surface throughout their entire length within the heat-transferring space of the exchanger.

2. In a heat exchanger of the class described, a shell, heat transferring tubes within 20 said shell and presenting an upper surface having a downward slope at every point throughout their entire length within the heat-transferring space of the exchanger and a lower surface reentrant with respect to 25 said upper surface to a sufficient degree to render said lower surface protected from condensate flowing over said upper surface.

3. A heat exchanger of the class described, comprising a shell for receiving heating 30 vapors and tubes for conducting another fluid into heat exchanging relation with said vapors, each of said tubes being longitudinally bowed from end to end and provided

with a longitudinally extending depression faced downwardly away from the precipitation of said condensing heating vapors. 31

4. A heat exchanger comprising a shell, tubes having a convex peripheral portion and a concave peripheral portion, said concave portion being faced downwardly away 40 from the precipitation of the condensing heating vapors, and supports for the ends of said respective tubes, said tube ends being of continuously convex periphery.

5. A heat exchanger of the class described 45 comprising a shell for containing the heating steam and tubes having end portions of circular section and intermediate portions distorted from a circular section a sufficient amount to effect a reduction in cross sectional area and having a downwardly faced depression, the transverse dimension of the intermediate portions of the tubes being less than the diameter of the circular portions 50 of said tubes. 55

6. A heat exchanger of the class described, comprising a shell providing a space for the heating steam and having a plurality of heat transferring tubes therein, each of said tubes having a convex upper surface and a broad, concave lower surface, bearing such a relation to the total tube surface, that substantially one-half of the total tube surface faces 60 away from the deposit of condensate.

In testimony whereof I affix my signature.
RUSSELL C. JONES.
